Primary Examiner — Karen S Acker(74) *Attorney, Agent, or Firm* — Fredrikson & Byron, P.A.(57) **CLAIM**

I claim the ornamental design for an ash collector for a stove, as shown and described.

DESCRIPTION

FIG. 1 is an upper rear perspective view of the ash collector for a stove of our design;

FIG. 2 is a left-side elevation view thereof;

FIG. 3 is a right-side elevation view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines in the drawings represent unclaimed environmental subject matter and form no part of the claimed design.
